(57) **CLAIM**

The ornamental design for a carafe, as shown and described.

DESCRIPTION

FIG. 1 is a top perspective view of a carafe showing our new design;

FIG. 2 is a front view of the carafe;

FIG. 3 is a back view of the carafe;

FIG. 4 is a right side view of the carafe;

FIG. 5 is a left side view of the carafe;

FIG. 6 is a top view of the carafe; and,

FIG. 7 is a bottom view of the carafe.

All of the broken lines in the drawings are included for the purpose of illustration and form no part of the claimed design.
